KNIFE SHARPENING MECHANISM

Hendrik Stukart, La Porte, Ind., assignor to U. S. Slicing Machine Company, La Porte, Ind., a corporation of Indiana

Application June 9, 1934, Serial No. 729,749

10 Claims. (Cl. 51—248)

This invention relates to slicing machines, and particularly to sharpening mechanism therefor.

The primary object of the invention is to provide a new and improved sharpening mechanism for slicing machine knives of the circular rotary type.

Another object of the invention is to provide sharpening mechanism for slicing machine knives whereby a pair of sharpening stones comprising a grinding stone and a burr removing stone are resiliently mounted and urged in a predetermined direction whereby the grinding stones have a resilient grinding action on the knife; the stones being maintained in a predetermined position by stop elements and having new and improved means for permitting quick and instant removal of the stones.

Numerous other objects and advantages will be apparent throughout the progress of the following specification.

The accompanying drawing illustrates a selected embodiment of the invention and the views therein are as follows:

Fig. 1 is a detail vertical sectional view through the improved sharpening mechanism showing the same out of contact with the knife but moved to grinding position as regards the knife.

Fig. 2 is a plan section thereof taken substantially along the line 2—2 of Fig. 1.

Fig. 3 is a detail elevation showing the position of the grinding stones as set forth in Fig. 1 looking from the right toward the left of the machine.

The slicing machine upon which the sharpening mechanism cooperates is of the type shown in the copending applications, Serial No. 718,583, filed April 2, 1934, and Serial No. 718,584, filed April 2, 1934. In the first mentioned copending application sharpening mechanism is disclosed in combination with a particular type of guard plate. In the second mentioned copending application sharpening mechanism of a similar type is shown and claimed but several of the features of the mechanism disclosed in this application are not disclosed; the present sharpening mechanism relating particularly to the specific arrangement and construction of the grinding stone mountings and the casing, whereby the housing, when turned, permits the stones to be freed, allowing them to move toward each other in their axes of rotation.

The slicing machine upon which the present sharpening mechanism is mounted and which is shown and disclosed in the aforesaid copending application, Serial No. 718,584, filed April 2, 1934, comprises a knife 16 which is rotatably mounted

on a knife supporting bracket 17. The supporting bracket 17 may comprise a part of the housing for the knife or the knife guard. A knife guard, as shown in the aforesaid copending application, Serial No. 718,584, filed April 2, 1934, is 5 adapted to extend about the periphery of the knife at the side opposite the operator.

A vertical spindle 18 is slidably supported in the supporting bracket member 17 and carries a housing 19 which is pivotally mounted thereon, being 10 held by a screw 20. The housing 19 comprises a body 21 and a portion 22 which may be pivotally attached at 23 to the housing by means of a hinge connection 24. A sharpener stone 25 is arranged on one side of the knife 16, Figs. 2 15 and 3, and constitutes the grinding stone. A second stone 26 is arranged on the other side of the knife and constitutes the burr removing stone.

The sharpener stone 25 is mounted on a shoulder spindle 27 and held thereto by a screw 28. 20 The spindle 27 is rotatably assembled in a sleeve 29 which is axially adjustable in a bearing 30 in the housing. The bearing 30 is removable from the spindle 18 but is rigidly connected thereto by a set screw (not shown). The spindle 27 is 25 axially held in the sleeve 29 by a washer 31 and a screw 32. The burr removing stone 26 is fastened to a spindle 34 by a screw 35, Fig. 2, and this spindle is rotatably mounted in a sleeve 36 which is axially movable in a bearing 37. The 30 bearing 37 is integrally connected to the bearing 30 by a connecting web 38. The spindle 34 is held against axial movement in the sleeve 36 by a washer 39 and a screw 39'.

The sleeve 29 has a smaller turned end providing 35 a recess 40 in which there is mounted a spring 41 for urging the spindle 27 to the left, Fig. 2. Anti-friction bearings 42 are arranged between the spindle 27 and the sleeve 29 as clearly indicated in Fig. 2. A side wall of the bearing 30 is 40 provided with a longitudinal slot 43, and a pin 44 which is fastened to the sleeve 29 protrudes outwardly through the slot 43. The pin 44 is adapted to abut against a stop pin 45 which is mounted on a supporting arm 46 and extends 45 through an opening 47 formed in the housing body 21. The arm 46 is made of spring material and normally tends to hold the stop pin 45 against the pin 44 as shown in Fig. 2. However, to remove the grinding stone 25, including the spindle 27 and the sleeve 29 from the bearing 30, the arm 46 is moved outwardly a predetermined distance to clear the stop pin 45 from the pin 44. The spring arm 46 may be fastened in any convenient 50 operable manner, such as by a fastening screw 48. 55

When it is desired to remove the grinding stone 25, including the spindle 27 and the sleeve 29, the housing cover 22 is swung on its pivot 23 and the spring arm 46 is moved outwardly to free the pin 45 from the pin 44 at which time the assembly may be removed from the bearing 30.

The sleeve 36 has a smaller turned end providing a recess 49 in which there is mounted a spring 50 for urging the spindle 34 to the right, Fig. 2. Anti-friction bearings 51 are arranged between the sleeve 36 and the washer 39 as clearly indicated in Fig. 2. A side wall of the bearing 36 is provided with a longitudinal slot 52, and a pin 53 which is fastened to the sleeve 36, protrudes outwardly through the slot 52. The pin 53 is adapted to abut against a stop pin 54 which threadedly engages the casing, Fig. 2. The arm spring 58 normally urges the sleeve 36 to the right but is held from assuming that position normally by the stop pin 54.

The spring 41 therefore urges the grinding stone outwardly from the casing (to the left) but is prevented from doing so by the engagement of the pin 44 with the stop pin 45; while the spring 50 urges the burr removing stone 26 inwardly of the casing (to the right) but is prevented from doing so by the engagement of the pin 53 with the stop pin 54. The integral bearing which comprises the parts 30, 37 and 38 is fixed to the shaft by means of a set screw 55 and engages a collar 56, Fig. 1, which is rotatably mounted on the spindle 18, being supported on the spindle shoulder 57. The freely mounted collar 56 is fixed to the casing by means of a set screw 58 which passes through the casing and the collar, Fig. 1. A spring 59 surrounds the spindle 18, and has its lower end anchored to the collar 56, and its upper end engaging a part of the integral bearing which comprises the parts 30, 37 and 38. The spring 59 therefore tends to cause rotative movement of the housing relative to the integral bearing but this rotative movement is prevented by the pins 44 and 45, and the pins 53 and 54. This urging action causes the pins 44 and 53 to be seated in the end of their respective slots 43 and 52. As previously mentioned, the casing 19 is pivotally connected to the spindle 18. Therefore when the casing 19 is manually rotated in a clockwise direction, Fig. 2, against the urging action of the spring 59, the springs 41 and 50 will move the grinding stones toward the cutting edge of the knife. The spring 59 tends to force the integral bearing 30, 37, 38 in a counterclockwise direction, but this urging action in a counterclockwise direction is limited by the pins 44 and 53 engaging the stop pins 45 and 54 respectively.

The vertical spindle 18 is slidably mounted in a boss 60 formed on the bracket 17, Fig. 1, and the lower end of the shaft or spindle 18 is provided with oppositely disposed vertical grooves 61 which are adapted to be engaged by a set screw 62 having a knurled thumb piece 63. The end of the set screw 62 is provided with a smooth pilot end 64 which fits into the groove, whereby the spindle 18 is adapted to have vertical slidable movement in the opening in the boss 60 but is normally prevented from rotating by the engagement of the pilot 64 with either one of the grooves or slots 61. The spindle 18 has a reduced lower end as indicated at 65, the reduced portion being substantially the diameter as the distance between the grooves 61. A knob 66 is formed on the bottom of the spindle 18, and this knob is substantially the same diameter as the normal diameter of the spindle 18. The spindle there-

fore is free to have vertical slidable movement in the boss 60, but is prevented from rotating by the engagement of the pilot 64 with a groove 61. The spindle may be raised upwardly until the upper surface of the knob 66 engages the lower surface of the set screw 62. In this latter position the smooth pilot end 64 will be at the reduced diameter of the spindle at which time the spindle is free to be rotated. As shown, the sharpening mechanism is in grinding position 10 as regards the knife 16, but the normal idle position of the sharpening mechanism is removed 180° from the position shown in the figures or in the position shown in dotted lines in Fig. 1. When the sharpening mechanism is 15 in its normal idle position, that is, away from the knife, the set screw 62 will engage one of the vertical slots 61; but when the sharpening mechanism is rotated 180° to knife sharpening position, the set screw will engage the other 20 groove 61 as shown in Fig. 2. In other words, the set screw engages one groove in idle position and engages the other groove in operating position when the sharpening mechanism has been rotated 180°, about its vertical axis. To rotate 25 the spindle, however, the spindle must be raised upwardly until the reduced diameter 65 is opposite the pilot 64 at which time the spindle can be turned until the other groove 61 is in position in respect to screw 62 when the spindle is again 30 lowered to bring the mechanism into sharpening position relative to the knife. A set screw 67 threadedly engages a part of the boss 60 and engages the set screw 62 to hold the set screw 62 in its proper operative locked position and 35 prevent unauthorized removal of the spindle 18. To remove the spindle 18 from the boss 60, the set screw 67 is first unscrewed to release its engagement with the screw 62. The set screw 62 can be rotated to move pilot end 64 out of the path 40 of the knob 66. The locking engagement of the set screw 67 with the set screw 62 may comprise a point on the end of the screw 67 engaging a groove provided in the set screw 62. A knurled nut 68, Fig. 1, threadedly engages the spindle 18 45 and rests upon the top of the boss 60. Rotation of the knurled nut 68 adjusts the sharpening mechanism vertically. A set screw 69 threadedly engaging the knurled nut 68 locks the knurled nut in adjusted position in respect to the shaft 50 or spindle 18. The knurled nut 68 adjusts the housing and its encased sharpening mechanism vertically to compensate for wear of the knife.

The invention provides compact, efficient, sharpening mechanism which is normally removed from the knife but which is brought into proper position in respect to the knife upon rotation of 180°. When it is desired to bring the stones into contacting engagement with the knife, the housing 19, top of Fig 1, is given a 60 clockwise twist or turn, which would appear as anti-clockwise in Fig. 2 because that is a view from below. This twist or turn causes no pressure to be exerted against the knife but merely compresses the spring 59 and moves the top pins 54 65 and 45 away from the pins 53 and 44, allowing the springs 41 and 50 to urge their respective stones into contacting engagement with the opposite sides of the knife. Both stones therefore are yieldingly urged into contacting or sharpening relationship with the knife by the springs arranged in the respective bearings. The grinding stone 25 can be freely and quickly replaced by manipulating the spring arm 46 to free the pin 44 from the stop pin 45. The pivotal engagement 70 75.

of the shield or cover plate 22 permits free and easy access to the interior of the casing 19.

Changes may be made in the form, construction and arrangement of the parts without departing from the spirit of the invention or sacrificing any of the advantages, and the right is hereby reserved to make all such changes as fairly fall within the scope of the following claims.

The invention is hereby claimed as follows:

1. In a slicing machine having a rotary knife, a sharpening mechanism therefor comprising a pair of sharpeners adapted to be arranged on opposite sides of the knife for straight line movement to and from the knife, a bearing and a resilient mounting for moving each sharpener into engagement with the knife, a casing in which said bearing and sharpeners are arranged, said casing being mounted on a vertical spindle and adapted to have rotary movement in respect thereto, stop means mounted on the casing for arresting action of the resilient mounting, said stop means being removable from arresting position by rotary movement of the casing thereby permitting movement of the sharpener into sharpening engagement with the knife by the resilient mountings upon said rotary movement of the casing.

2. In a slicing machine having a rotary knife, a sharpening mechanism therefor comprising a pair of sharpeners arranged on opposite sides of the knife for straight line movement, a bearing for said sharpeners, a casing for housing the bearing and sharpeners, said casing adapted for rotation about a vertical support, resilient means for urging one sharpener toward the bearing and the other sharpener away from the bearing, said resilient means being normally restrained from moving the sharpeners into contacting relationship with the knife, said restraint being removed by rotation of the casing in a predetermined direction.

3. In a slicing machine having a rotary knife, a sharpening mechanism therefor comprising a pair of sharpeners arranged on opposite sides of the knife, a bearing for said sharpeners, a resiliently mounted casing for housing the bearing and sharpeners, said casing adapted to be manually rotated, springs urging one sharpener in one direction and the other sharpener in the opposite direction, stop pins for holding the sharpeners in a predetermined position, rotatable movement of the housing freeing the stop pins and permitting the springs to urge the sharpeners into sharpening engagement with the knife.

4. In a slicing machine having a rotary knife, a sharpening mechanism therefor comprising a pair of sharpeners arranged on opposite sides of the knife, a bearing for said sharpeners, a support, a casing rotatably mounted on the support and adapted for rotative movement in respect to the support, said casing housing the bearing and sharpeners, said bearing having slots therein, pins operatively connected to the sharpeners and extending through said slots, sharpener springs, and stop means engageable with said pins for limiting the movement of the first named pins, said stop pins being moved away from the first named pins upon rotative movement of the casing whereby the sharpener springs will move the sharpeners into contacting relationship with the knife.

5. In a slicing machine having a rotary knife, a sharpening mechanism therefor comprising a

pair of sharpeners arranged on opposite sides of the knife, a bearing for said sharpeners, a support, a casing rotatably mounted on said support for housing the bearing and sharpeners, springs urging one sharpener in one direction and the other sharpener in the opposite direction, stop pins for holding the sharpeners in a predetermined position, rotatable movement of the housing on its support freeing the stop pins and permitting the springs to urge the sharpeners into sharpening engagement with the knife, a revolvably mounted longitudinally slid able spindle for said mechanism, and means for locking the spindle in predetermined positions.

6. In a slicing machine having a rotary knife, a sharpening mechanism therefor comprising a pair of sharpeners arranged on opposite sides of the knife, a bearing for said sharpeners, a support, a casing rotatably mounted on said support and housing the bearing and sharpeners, said bearing having slots therein, pins operatively connected to the sharpeners and extending through said slots, sharpener springs, stop means engageable with said pins for limiting the movement of the first named pins, said stop pins being moved away from the first named pins upon rotative movement of the casing whereby the sharpener springs will move the sharpeners into contacting relationship with the knife, a revolvably mounted longitudinally slid able spindle for said mechanism, and means for locking the spindle in predetermined positions.

7. In a slicing machine having a rotary knife, a sharpening mechanism therefor comprising a pair of sharpeners arranged on opposite sides of the knife, a bearing for said sharpeners, a support, a casing adapted for rotative movement on the support for housing the bearing and sharpeners, said bearing having slots therein, pins operatively connected to the sharpeners and extending through said slots, sharpener springs, and stop means engageable with said pins for limiting the movement of the first named pins, said stop pins being moved away from the first named pins upon rotative movement of the casing whereby the sharpener springs will move the sharpeners into contacting relationship with the knife, said casing having a slot therein, one of said stop pins being hingedly connected to the casing and passing through said slot in the casing.

8. In a slicing machine having a rotary knife, a sharpening mechanism therefor comprising a pair of sharpeners arranged on opposite sides of the knife, a bearing for said sharpeners, a support, a casing adapted for rotative movement on the support for housing the bearing and sharpeners, said bearing having slots therein, pins operatively connected to the sharpeners and extending through said slots, sharpener springs, stop means engageable with said pins for limiting the movement of the first named pins, said stop pins being moved away from the first named pins upon rotative movement of the casing whereby the sharpener springs will move the sharpeners into contacting relationship with the knife, a revolvably mounted longitudinally slid able spindle for said mechanism, and means for locking the spindle in predetermined positions, said casing having a slot therein, one of said stop pins being hingedly connected to the casing and passing through said slot in the casing.

9. In a slicing machine having a rotary knife,

- a sharpening mechanism therefor comprising a pair of sharpeners arranged on opposite sides of the knife, a bearing for said sharpeners, a revolubly casing for housing the bearing and sharpeners, springs urging one sharpener in one direction and the other sharpener in the opposite direction, stop pins for holding the sharpeners in a predetermined position, rotatable movement of the housing freeing the stop pins and permitting the springs to urge the sharpeners into sharpening engagement with the knife, a spindle for said casing, and a support for the spindle, said spindle being rotatable 180° on said support.
- 10 15 10. In a slicing machine having a rotary knife,

a sharpening mechanism therefor comprising a pair of sharpeners arranged on opposite sides of the knife, a bearing for said sharpeners, a revolubly mounted casing for housing the bearing and sharpeners, springs urging one sharpener in one direction and the other sharpener in the opposite direction, stop pins for holding the sharpeners in a predetermined position, rotatable movement of the housing freeing the stop pins and permitting the springs to urge the sharpeners into sharpening engagement with the knife, and a hinged cover on the casing to permit withdrawal of the sharpeners from one side of the casing.
